UNITED STATES PATENT OFFICE.

HENRY LECHTENBERG, OF QUINCY, ILLINOIS.

CRUSHER.

1,039,062.

Specification of Letters Patent. Patented Sept. 17, 1912.

Application filed December 27, 1909. Serial No. 535,171.

To all whom it may concern:

Be it known that I, HENRY LECHTENBERG, a citizen of the United States of America, residing at Quincy, in the county of Adams 5 and State of Illinois, have invented certain new and useful Improvements in Crushers, of which the following is a full, clear, and exact description, reference being had to the accompanying drawings, forming part of 10 this specification.

My invention relates to a crusher that is adapted to crush and separate various kinds of material, the crusher herein shown being more particularly adapted to break the 15 coke and cinders which remain in foundry cupolas after molten metal has been poured therefrom. When used for this purpose, the apparatus also separates the coke and particles of metal which are mixed with the 20 cinders.

Figure I is a side elevation, partly in section. Fig. II is an end view, partly in section. Fig. III is a vertical section, taken on line III—III, Fig. I. Fig. IV is a section taken on line IV—IV, Fig. III. Fig. V is a section taken on line V—V, Fig. I. Fig. VI is a section taken on line VI—VI, Fig. V.

In the accompanying drawings:—A indicates a tank upon which standards 1 are mounted, a drum B being journaled in said standards. A drive pulley 2 is connected to a shaft 3 by clutch mechanism E. This clutch mechanism forms no part of my invention and I, therefore, do not deem it necessary to show or describe the details of its construction.

4 indicates a pinion, (see Fig. II), secured to the shaft 3 and meshing with a gear 40 wheel 5, the latter being fastened to the rotatable drum B.

When rotary motion is imparted to the drum B, the material contained therein is crushed by a bar 6 loosely arranged in said 45 drum. The material to be acted on by the crusher is introduced into the drum through an opening that is normally closed by a door 7. This door is provided with suitable locking means which form no part of 50 the present invention.

In addition to being crushed, the material is acted on by a constantly running stream of water forced through the drum B by a pump F. The pump is driven by a shaft 12, provided with a pinion 13 which meshes with a bevel gear 14, the latter being secured to the

drive shaft 3. Water is discharged from the pump through a pipe 15 leading to a stuffing box 16 on the end of a hollow trunnion 17. The opening 18 in the trunnion 60 17 constitutes the inlet port of a hollow head C, for the drum B, and which I will designate the inlet head, (see Fig. III). The inlet head has an annular flange 19 on its inner face and is provided with inclined 65 non-radial ribs 20 which constitute partitions dividing the head into compartments and extend from points adjacent the inlet port to the flange 19. The ribs 20 are preferably integral with the flange 19 and shaped 70 so as to form angular pockets 21 adjacent the periphery of the inlet head C. The flange 19 and ribs 20 are covered by a pair of semi-circular plates 22 secured to the inlet head by screws 23. The plates 22 are 75 provided with openings 24, which register with the pockets 21 and allow water to pass from the inlet opening 18 to the interior of the drum B.

Prior to this invention, crushers have been 80 provided with a hollow inlet head and a perforated plate forming the inner wall of said head. These perforated plates allow the water to take the path of least resistance and thereby enter the drum at a point above 85 the crushed material. The structure herein shown causes the water to be discharged only into the lower portion of the drum where the crushed material is located.

The discharge head D is provided with 90 an annular flange 19^a, inclined non-radial ribs 20^a which constitute partitions dividing the head into compartments, angular pockets 21^a, and cover plates 22^a, having openings 24^a which register with said pockets. 95 The water passes into the hollow head D through openings 24^a and is discharged therefrom through an opening 25 in a trunnion 26.

When this apparatus is used to crush cinders with which coke and particles of metal are mixed, its action is as follows: The drum revolves in the direction indicated by the arrows in Figs. III and V, and the material is crushed by the bar 6. Some of 100 the heavy material enters the pockets in the inlet head and is carried by said pockets to a point above the main body of material. These pockets have inclined walls which cause their contents to be discharged by 105 gravity at a point above the water level. Coke and cinders entering the inlet head 110

tend to rise to the water level, but are prevented from doing so by the pockets 21 and ribs 20. It will be seen that light material entering the head at M or N, Fig. III, is prevented from rising and retained in the pockets by the ribs 20. At O the light material is free to rise, but as the drum revolves, this material is picked up by an inclined rib and discharged into the drum at P or Q. At the discharge end of the drum, the coke and cinders which enter the pockets 21 are free to rise at S and float toward the discharge opening 25. If any of this light material is carried in the pockets to a point above the water level, it is discharged therefrom at T and is moved toward the discharge opening 25 by the inclined ribs. It will now be understood that the coke and cinders are allowed to enter the discharge head and pass out through opening 25 with the water. The discharged water and finely ground cinders pass through perforations in a cylinder 28, (see Fig. I), while the coke passes out through the end of said cylinder and falls into a receptacle 29. The

particles of metal which are "scooped up" by the pockets of the discharge head D are discharged into the drum at U or V. However, if any of these heavy particles should remain in the pockets and pass to the point indicated by T, they will simply fall and be again "scooped up" by the pockets during a later revolution of the drum. 30

I claim:

A hollow inlet head for a crusher drum comprising an outer wall provided with an inlet opening, an inner wall having discharge openings, ribs extending from each discharge opening to a point adjacent to the inlet opening, each of said ribs being substantially L-shape at the discharge opening to form a pocket for receiving material passing into the head, said ribs being inclined to serve as guides for deflecting the material in said head and causing it to pass 40 out through the discharge openings. 45

HENRY LECHTENBERG.

In the presence of—

WALTER A. HEIDBREDER,
H. C. SPRICK.
